UNITED STATES PATENT OFFICE.

JOHN BLASZCZYK, OF NEW YORK, N. Y.

KEY.

939,184.

Specification of Letters Patent.

Patented Nov. 2, 1909.

Original application filed March 19, 1909, Serial No. 484,353. Divided and this application filed May 28, 1909. Serial No. 498,394.

To all whom it may concern:

Be it known that I, JOHN BLASZCZYK, a subject of the Czar of Russia, and resident of the city of New York, in the county of 5 Kings and State of New York, have invented certain new and useful Improvements in Keys, of which the following is a specification, being a division of application for Letters Patent, Serial No. 484,353, filed 10 March 19, 1909.

The present invention relates to keys for locks, and more particularly to keys for permutation locks.

The permutation lock, described in application for Letters Patent, Serial No. 484,353, filed March 19, 1909, of which the present application is a division, comprises two independent tumblers controlling a locking bolt. One of these is a rotatable tumbler, controlled by a permutation mechanism, while the other is operated by a key. When a certain combination is set, the rotatable tumbler must be turned through a predetermined angular distance to release 25 the locking bolt, and at the same time the other tumbler raised to a certain height, depending upon the combination set, so as to be disengaged from the locking bolt simultaneously with the tumbler controlled 30 by the combination.

The object of the present invention is to provide a key which is normally incapable of performing its functions, but which may be readily set by one familiar with its operation and with the combination of the lock, so that it may, first, after a given number of turns, bring the rotatable tumbler, controlled by the combination mechanism, into a position, whereby the locking bolt is released by the same, second, raise the other tumbler for a similar purpose, and, third, retract the locking bolt or bolts after the tumblers are set properly.

A further object of the invention is to 45 provide a key, consisting of a tumbler operating part and of a locking bolt retracting part, and to combine said two parts in such a manner that the same will not interfere with each other in their operation.

50 With these and other objects in view, the invention consists of a key stem and a bit, upon which are shiftably arranged a plurality of cams, and a secondary key arranged on said stem.

The invention is illustrated in the accompanying drawings, in which—

Figure 1 is a sectional elevation of the key, forming the subject matter of the present application for Letters Patent, Fig. 2 is a section taken on line 2, 2 of Fig. 1, on an enlarged scale, Fig. 3 a side elevation of the shiftable cams and their shifting means, Fig. 4 is a front elevation of the means indicating the positions of the cams upon the key-bit, and Fig. 5 is a section taken on line 5, 5 of Fig. 1.

The key illustrated comprises a stem 6, having a bit 7, upon which is mounted a cam-wheel 8, arranged in a plane at right angles to the plane of the bit. This cam-wheel comprises in the present case four cams 9, 10, 11 and 12, of increasing length, and is fixedly attached to a spindle 13, rotatably mounted in said key-bit and being provided with an operating knob 14, provided with marks 15, 15, corresponding to the four cams of the cam-wheel. To the spindle 13 is furthermore attached a disk 16, provided with recesses 17, 17, corresponding in number to the number of the cams of the cam-wheel. A spring 18 is provided upon the bit of the key and engages, when a cam of the cam-wheel is set to its operating position, its corresponding recess 17, to keep said cam-wheel in the desired position. The stem 6 carries furthermore slidably thereon a sleeve 19, provided with a bit 20 upon its outer end, and with a knob 21 upon its inner end for operating said bit 20. The main bit 7 of the key is recessed at 22, and the sleeve 19 in a similar manner at 23, allowing thereby of the longitudinal shifting of said sleeve into a position, whereby the bit 20 may actuate the locking bolt retracting means, arranged substantially in the plane of the tumblers, which are operated by the main bit 7.

In operation, the knob 14 is turned to bring the proper cam in the operative position. The key is then inserted into the lock 100 in such a manner that the sleeve 19 and therewith the bit 20 is kept in its outer position, that is in a position whereby the inner end of the sleeve contacts with the bow of the key. The main bit of the key is now 105 turned a number of times, depending upon the combination set, whereby the said bit will turn the rotating tumbler through a

certain angular distance, and raise and lower the other tumbler accordingly. If the proper cam is set upon the bit, the second tumbler will be raised by the said cam 5 during the last turn of the key so as to disengage the locking bolt at the moment the rotating tumbler releases the same. Inserting now the sleeve 19 into the key of the lock, the bit 20 thereof may be turned to 10 retract the released locking bolt.

What I claim is:

1. In a key, the combination with a stem, of a key bit thereon, a plurality of cams arranged on said bit in a plane at right angles to the plane thereof, means for shifting said cams through certain angles, and a secondary key slidably arranged on said stem. 15
2. In a key, the combination with a stem, of a key bit thereon, a plurality of cams arranged on said bit in a plane at right angles to the plane thereof, means for shifting said cams upon said bit in their operating plane, 20

means for determining the positions of said cams, and a secondary key shiftably ar- 25 ranged on said stem.

3. In a key, the combination with a stem, of a key bit thereon, a plurality of cams ar- 30 ranged on said bit in a plane at right angles to the plane thereof, and means for shifting said cams through certain angles.

4. In a key, the combination with a stem, of a key bit thereon, a plurality of cams ar- 35 ranged on said bit in a plane at right angles to the plane thereof, means for shifting said cams upon said key bit in their operating plane, and means for predetermined the positions of said cams.

Signed at New York, in the county of New York and State of New York, this 19th 40 day of May, A. D. 1909.

JOHN BLASZCZYK.
